UNITED STATES PATENT OFFICE.

WILLIAM F. TUBESING, OF CINCINNATI, OHIO.

MACHINE FOR MAKING CONCRETE BLOCKS.

No. 868,730.

Specification of Letters Patent.

Patented Oct. 22, 1907.

Application filed May 20, 1907. Serial No. 374,541.

To all whom it may concern:

Be it known that I, WILLIAM F. TUBESING, a citizen of the United States of America, and a resident of Cincinnati, county of Hamilton, State of Ohio, have invented certain new and useful Improvements in Machines for Making Concrete Blocks, of which the following is a specification.

The object of my invention is a machine having a mold in which concrete blocks are formed, in which 10 the operation of removing a block when formed from the mold makes a minimum amount of delay in the process of forming the next block therein, in which the movement of the machine automatically releases the block from the mold and carries it onto the unloading 15 station and automatically closes the walls of the mold, which is provided with a means of supplying the proper amount of loose material to the mold uninterruptedly and which has an efficient means of forming hollow blocks. This object is attained by the means described 20 in the specification and illustrated in the accompanying drawings, in which,

Figure 1 is a plan view of a machine for making concrete blocks embodying my invention, the standards for supporting the engine which actuates the tamping 25 block being omitted. Fig. 2 is a central longitudinal sectional view of the same taken upon line $x-x$ of Fig. 1. Fig. 3 is an end view, but showing the mold in section upon line $y-y$ of Fig. 2. Fig. 4 is a detail perspective view upon an enlarged scale, of the reciprocating carriage, which has partitions for forming the 30 ends of the mold and the tracks upon which is mounted the car which carries the block to form the bottom of the mold. Fig. 5 is a detail perspective view of the swinging door which forms one of the sides of the mold 35 between which the carriage reciprocates. Fig. 6 is a detail sectional view similar to Fig. 2, upon an enlarged scale, showing a modification for use in forming hollow blocks, the swinging ends of the carriage not being shown. Fig. 7 is a sectional view upon line $z-z$ of 40 Fig. 6.

Referring to the parts: The mold consists of longitudinal non-reciprocating vertical sides, a , a' . The fixed partition, b , of the carriage, B , alternately forms the left and then the right hand end of the mold; the hinged 45 sides, b' , and b'' , alternately forming the left and then the right hand end of the mold, the bottom of the mold being formed by a board, e , which is carried upon one of the cars, C , which is mounted upon the tracks of the carriage, B , the top of the mold being formed by 50 the tamper, D , which is reciprocated by the engine, d . The carriage, B , is mounted upon longitudinal ways, e , of the frame, E , and is reciprocated by an engine, F , so as to bring the partition, b , of the carriage alternately first to one end and then to the other end of the funnel, 55 G , which is mounted upon the walls, a , a' , of the mold. The carriage, B , is steadied upon its ways, e , by a longi-

tudinal rod, E' , which is secured to the ends of the frame, E , and passes through a longitudinal slot, B' , in the carriage. The ends, b' , b'' , are hinged at b^3 , b^4 , to the carriage and have their lower ends projecting 60 downwardly so that when the carriage reaches either the left hand or the right hand end of its travel, the lower end of the doors, b' , b'' , come into contact with lugs, e' , e'' , of the frame and are thereby thrown outward as illustrated at the right hand sides of Figs. 1, 2 65 and 4. Rod, E' , is enlarged at the center, e^3 , so that when the ends of the carriage have reached the innermost limit of their travel e^3 strikes the lower ends of the doors, b' , b'' , and bring them to their vertical position, such as is illustrated upon the left hand side of Fig. 2. 70 The floor, b^5 , of the carriage is formed at an incline to the horizontal and has parallel tracks, b^6 , b^7 , b^8 and b^9 upon opposite sides of the partition, b , and formed at an acute angle to the sides of the carriage. When the carriage is at the right hand limit of its travel, the tracks, 75 b^6 , b^7 , register with tracks, h , h' of an unloading station, H , and when the carriage is at the left hand limit of its travel, the tracks, b^8 , b^9 , register with tracks, h^2 , h^3 , of a second unloading station, H' . The tracks, b^6 , b^7 , b^8 , and b^9 receive cars, C , with sets of wheels, the axles 80 of which are placed in relation to the body of the car, such that when on the tracks, the board, e , carried by the car, is on a level. At the sides of the funnel, G , are located two hoppers, M , M' , of a size such as to accommodate a charge of loose material sufficient to form 85 a block.

The engine, d , may be run by steam admitted through pipes, d' , d'' , or by any other source of power, such as water under pressure.

Both non-reciprocating sides of the mold will be 90 formed in one piece in those machines in which it is desired to make simply blocks having plain parallel faces. In case it is desired to make blocks having an outer face which has a configuration which is not plain, I form a hole in the wall, a' , as illustrated in Fig. 5 95 and close the same by a swinging door, a^2 , which is pivoted upon a lug, a^3 , projecting from the side, a' , at the bottom of the door. When in position to close the hole in the wall, a' , the door, a^2 , is held by rods, a^4 , a^5 , which engage a rod, a^6 , held by a stud, a^7 , which projects from the door, a^2 . The inner ends of the rods, 100 a^4 , a^5 , engage lugs, a^8 , which project from the sides, a' . The rods, a^4 , a^5 , have spurs, a^9 , a^{10} , which contact the door, a^2 , to hold it in place. When it is desired to allow the carriage to reciprocate after a block has been 105 formed, the rods, a^4 , a^5 , are withdrawn from the rod, a^6 , and the door may then be swung downward about the lug, a^3 . To the inner face of the door, a^2 , the form, a^{10} , is secured. This form may be of any desired configuration to give the desired contour to the face of the 110 block.

The operation of the device is as follows: When the

reciprocation of the engine, F, brings the partition, b, to the right hand side of the funnel, G, as shown in Fig. 2, the end, b', striking the block, e³, is brought to its vertical position. The charge from either the hopper, M, or M', being discharged into the funnel, G, the tamper, D, by the reciprocation of the engine, tamps the loose material into the mold between the board, c, the tamper, D, the partition, b, the side, b', and the non-reciprocating sides, a, a'. If the block being formed has plain faces, which will be the case when the form, a¹⁰, is plain, after the block has been formed, the engine, F, is actuated to move the carriage, B, to the left hand limit of its travel, when the lower end of side, b', will strike the lug, e', and be thrown outward. The newly formed block being thus released from contact between the walls, b', and b, gravity will cause the cars, C, to move on to the tracks, h², h³, of the unloading station, H'. The newly formed block is then removed from the car and the car is moved upward upon the tracks, b⁸, b⁹. In the meantime, while this operation of removing the newly formed block from the left hand end of the carriage has been proceeding, the partition, b, having come to the left hand end of the funnel, G, and the end, b', having been carried to its vertical position at the right hand end of the funnel by the block, e³, another block has been formed by the time the block has been removed from the left hand end of the carriage and the car has been placed back in position again. The carriage, B, is then reciprocated to the right, as shown in Fig. 2, when the operation of removing the block formed upon the right hand side of the partition is carried on in a manner similar to that just described. Thus the operation of forming a block is being performed while the operation of removing a block just formed has progressed so that no time is lost in the use of the machine. In cases in which the configurated form, a¹⁰, is used, it is necessary to open the door, a², before reciprocating the carriage after the block has been formed. In the form shown in Fig. 6, and Fig. 7 for making hollow blocks, carriage, B', has in its floor two perforations below which are two vertical posts, b¹⁰, b¹¹, which are formed to enter the central bores in cores, K, K'. The carriage has upwardly projecting standards, b¹², b¹³, upon which the floor, b⁵, is carried and the engine, F, in place of being centrally located in reference to the frame, E², is placed to one side and engages one of the standards, b¹³, for reciprocating the carriage, B'. Horizontal bars, e⁵, e⁶, are secured to the ends of the frame, E², and have ledges, e³, e⁴. Ledges, e³, e⁴, stand upon each side of the posts, b¹⁰, b¹¹, terminate at points within the points to which the posts b¹⁰, b¹¹, are carried when the carriage, B', is moved to the left hand and to the right hand limit of its travel as shown in Fig. 6. Upon ledges, e³, e⁴, the cores, K, K', move when the engine reciprocates the carriage. To the ends of the frame, E², levers, e¹⁵, e¹⁶, are pivoted and the ends of the levers, e¹⁵, e¹⁶, are bi-furcated so as to straddle the posts, b¹⁰, b¹¹, when they are at the left or right hand limits of their travel, as shown in Fig. 7. When the carriage is moved to the right hand limit of its travel, as shown in Fig. 6, core, K', being no longer supported by the bars, e³, e⁴, slides upon the post, b¹¹, carrying the lever, e¹⁶, downward. The car, C, is then free to move on to the unloading station.

After the block has been removed and the car has been moved back upon the carriage, the core, K', is raised by means of the lever, e¹⁶, to come to the level of the bars, e³, e⁴, and then the reciprocation of the carriage, B', will carry the core, K', onto the bars, e³, e⁴. It will be thence borne to its position within the mold.

What I claim is:

1. In a block molding machine the combination of vertical longitudinal sides fixed at a distance apart, a carriage mounted to reciprocate between said sides, transverse plates secured to the carriage for alternately forming one end of the mold and a transverse partition fixed upon the carriage between the plates for forming the other end of the mold, a plate upon the carriage forming the bottom of the mold, a means for feeding loose material into the molds, a tamper and a means for reciprocating the carriage.

2. In a block molding machine the combination of vertical longitudinal sides fixed at a distance apart, a carriage mounted to reciprocate between said sides, transverse plates hinged to the carriage for alternately forming one end of the mold and a transverse partition fixed upon the carriage between the hinged plates for forming the other end of the mold, a plate upon the carriage forming the bottom of the mold, a means for automatically moving the swinging plates to release a block and to resume their operative position, a means for feeding the loose material into the molds, a tamper and a means for reciprocating the carriage.

3. In a block molding machine the combination of vertical longitudinal sides fixed at a distance apart, a carriage mounted to reciprocate between said sides, transverse plates secured to the carriage for alternately forming one end of the mold and a transverse partition fixed upon the carriage between the plates for forming the other end of the mold, a plate upon the carriage forming the bottom of the mold, twin hoppers for feeding loose material into the molds, a tamper and a means for reciprocating the carriage.

4. In a block molding machine the combination of two vertical sides at a distance apart and parallel to each other, a carriage mounted to reciprocate between said sides, the floor of the said carriage being made slanting, plates hinged to the carriage for alternately forming one end of the mold and a partition upon the carriage between the hinged plates for forming the other end of the mold, tracks upon the carriage upon each side of the partition, cars mounted upon the tracks for forming the bottoms of the molds, unloading stations at the ends of the travel of the carriage, a means for automatically moving the swinging plates to release the cars to allow them to move upon the unloading stations, a means for feeding the loose material into the mold, a tamper, and a means for reciprocating the carriage.

5. In a block molding machine the combination of two vertical sides at a distance apart and parallel to each other, a carriage mounted to reciprocate between said sides, the floor of said carriage being made slanting and being perforated, plates hinged to the carriage for alternately forming one end of the mold and a partition upon the carriage between the hinged plates for forming the other end of the mold, tracks upon the carriage upon each side of the partition, cars mounted upon the tracks for forming the bottoms of the molds, unloading stations at the ends of the travel of the carriage, a means for automatically moving the swinging plates to release the cars to allow them to move upon the unloading stations, a means for feeding the loose material into the mold, a tamper, cores to engage the perforations in the bottom of the carriage, means for holding the cores upward while the carriage is reciprocating, and means for automatically lowering the cores at the ends of the travel of the carriage to release the cars.
